(57) **CLAIM**

The ornamental design for a lawn mower, as shown.

DESCRIPTION

FIG. 1 is a perspective view of a lawn mower;
FIG. 2 is a side view thereof;
FIG. 3 is another side view thereof;
FIG. 4 is a front view thereof;
FIG. 5 is a rear view thereof;
FIG. 6 is a top view thereof; and,
FIG. 7 is a bottom view of a lawn mower showing the claimed design.

The broken lines in the drawings depict portions of the lawn mower or environmental structures that are not part of the claimed design.

1 Claim, 7 Drawing Sheets
